The original design for a christmas candle holder, substantially as shown and described.

DESCRIPTION

FIG. 1 is a top plan view of a christmas candle holder showing my new design;

FIG. 2 is a side elevational view thereof;

FIG. 3 is a cross-sectional view thereof taken along line 3—3 of FIG. 1;

FIG. 4 is a top plan view of a second embodiment of my design; and,

FIG. 5 is a cross-sectional view thereof taken along line 5—5 of FIG. 4.

The holder is broken away in all figures to indicate indeterminate length.

The candle is shown in broken lines in FIGS. 3 and 5 for illustrative purposes only.
